UNITED STATES PATENT OFFICE.

JOHN STEVENSON, JR., OF PORTOBELLO, SCOTLAND.

AUTOMATIC SUSPENSION AND CONTACT APPLIANCE FOR ELECTRIC-ARC LAMPS.

SPECIFICATION forming part of Letters Patent No. 778,911, dated January 3, 1905.

Application filed December 22, 1903. Serial No. 186,224.

To all whom it may concern:

Be it known that I, JOHN STEVENSON, Jr., electrical engineer, a subject of the King of Great Britain, and a resident of Rowan Bank, 5 Durham Road, Portobello, Scotland, have invented an Improved Automatic Suspension and Contact Appliance for Electric-Arc Lamps and other Apparatus Requiring to be Raised and Lowered, of which the following is 10 a specification.

This invention relates to a suspension and contact appliance for electric-arc lamps and such like requiring to be raised and lowered; and its object is to provide means whereby 15 when an arc-lamp or the like is drawn up into position its weight shall be taken off the lowering and raising chain or rope and at the same time the lamp shall be automatically connected into correct electrical circuit and 20 its weight utilized for making a sound electrical contact.

On the drawings annexed, Figure 1 is a vertical section of the device. Fig. 2 is a horizontal section taken on the line XX and looking from below. Fig. 3 is an inverted plan view of the socket.

The arrangement shown on the drawings is for three electrical contacts.

The device, which takes the form of a dome 30 or bell *a*, is secured to the lamp-pillar, preferably by means of a socket-joint *b*. In the dome are four suspenders *c*, two of them being shorter than the other two. The short suspenders are arranged opposite one another, 35 and so also are the long suspenders. Each suspender has a contact step or hook *d* at its lower end, and the contacts of the short suspenders are adapted to engage with the annular inverted-trough-shaped contact *e* of the socket *f*. The sockets *f* and *h* and the plug *i* are made of porcelain or other insulating 40 material and are of the shape shown. Each hook *d* has a hinged shutter *j*, of triangular shape and which is capable of closing or covering the hook. Above the socket *f* is a tubular or telescopic contact *k l*, provided with

an inner insulating-sleeve *m*. The sockets 50 are jointed together by means of the bolt *o*.

p is the raising and lowering rope for the lamp.

q is the electric cable leading to the long 55 suspenders *c*.

r is the cable leading to the short suspenders.

s is the cable leading to the central pole or contact *k*. The cable *t* from the lamp *u* passes to the tubular contact *l*. The cable *v* from 60 the lamp passes to the annular contact *e*, and the cable *w* from the lamp passes to the annular contact *g*.

x represents bent guide-rods arranged in 65 the dome or bell.

The action of the appliance is as follows: The dome remains in position at the end of the swan-neck of the lamp-pillar and is free to swivel on its socket-joint. The sockets *f h* are raised and lowered with the lamp by means 70 of the cord *p*. When the sockets and lamp are drawn up, the sockets are guided into the bell by means of the guide-rods *x*, and the beveled edge of the top socket *f* strikes against the wedge-shaped ends of the suspenders and 75 forces them out. At the same time the edge of the socket strikes against the shutters *j* and raises them up, (see dotted lines,) so that when the lamp is again lowered the suspenders move inward and engage with the annular trough-shaped contacts *e g*. The engagement of the contacts of the suspenders with the contacts *e g* closes the circuits. The raising of the sockets of course causes the telescopic contacts *k l* to engage. To disengage 80 the contacts and lower the lamp, the sockets are raised sufficiently high to disengage the step-contacts and allow the shutters to fall down and close the steps. The sockets and lamp can now be lowered, and in falling the beveled edge of the socket *h* impinges on the 85 inclined back of the shutters, and as a consequence forces the suspenders back out of the way. It will be seen that when the contacts are engaged the weight of the lamp is thrown 90 onto the steps of the suspenders, so that the whole weight is utilized so as to give correct electric contact. Further, as the contacts *e g* 95

are turned downward they are not liable to gather rain, and so short-circuit.

Having now fully described my invention, what I claim, and desire to secure by Letters 5 Patent, is—

1. In a suspension and contact appliance for electric-arc lamps and such like requiring to be raised and lowered the combination of suspenders having step-contacts with an insulated 10 socket having an annular inverted-trough-shaped contact therein the step-contacts of the suspenders being adapted to automatically engage with the contact of the socket substantially as described.
- 15 2. In a suspension and contact appliance for electric-arc lamps and such like requiring to be raised and lowered the combination of a bell, suspenders pivoted to the bell, contacts on the suspenders, means for conveying an 20 electric current to the suspenders, an insulated socket, an annular inverted-trough-shaped contact therein, means for electrically connecting the socket to the lamp or such like, and means for raising and lowering the socket 25 substantially as described.
3. In combination, a case, freely-moving 30 suspenders arranged within the case, means for conveying an electric current to the suspenders, step-contacts on the suspenders shutters for closing the steps, an insulated socket arranged within the case an annular contact in the socket electrically connected with an

arc-lamp and means for raising and lowering the socket and lamp substantially as described.

4. In combination, a case, freely-moving 35 suspenders arranged within the case, means for conveying an electric current to the suspenders, step-contacts on the suspenders, shutters for closing the steps, insulated sockets arranged within the case and one above the 40 other, annular contacts in the sockets—said contacts being electrically connected with an arc-lamp, means for securing the sockets together, and means for raising and lowering the 45 sockets and lamp substantially as described.

5. In combination, a case, freely-moving 50 suspenders arranged within the case, means for conveying an electric current to the suspenders, step-contacts on the suspenders, shutters for closing the steps, insulated sockets arranged within the case and one above the 55 other, annular contacts in the sockets, a telescopic contact arranged above the sockets, said contacts being electrically connected with an arc-lamp, means for securing the sockets together, and means for raising and lowering the sockets and lamp, substantially as described.

Signed at Glasgow this 10th day of December, 1903.
